Mitchell Miller.

UNITED STATES PATENT OFFICE.

MEDOREM W. GREER, OF NEW YORK, N. Y.

MASTER-LAST.

1,226,071.

Specification of Letters Patent. Patented May 15, 1917.

Application filed September 7, 1916. Serial No. 118,820.

To all whom it may concern:

Be it known that I, MEDOREM WILLIAM GREER, a citizen of the United States of America, residing at New York city, county 5 and State of New York, have invented a new and useful Master-Last, of which the following is a specification.

My invention relates to new and useful improvements in the manufacture of master 10 lasts, that is to say, a last which is suitably modeled by hand, or otherwise, and which is to be employed in an automatic modeling machine, for the purpose of reproducing in wood, or other appropriate material, corresponding 15 devices.

The object of the present invention is to provide certain new and useful improvements whereby comparatively fragile composition material may be successfully employed as the model or master last.

In the drawings:

Figure 1 is a side elevation, partly in section.

Fig. 2 is a longitudinal section showing 25 the core in elevation.

1 represents the main body or last, which is formed from some plastic compound or material that may be readily fashioned into the desired shape. Plaster of Paris is one 30 such material that may be successfully employed by my improved construction. My improved construction contemplates extending longitudinally through the material a core, preferably metallic, which core has an 35 irregular cross section at a suitable point or points intermediate its length, whereby when the composition of the body has hardened thereon, the core cannot be turned without turning the body, that is to say, the 40 core is locked therein against movement in all directions. In this instance, the core comprises a pipe having two ends 2—3 and an intermediate flattened portion 4, which gives to the same an irregular cross section 45 that will lock into the body of the material when the latter is hardened. One end of the reinforcement, for example, the end 3, may

be notched to receive a pin or dog of a turning lathe, the centers of which may be engaged with the ends of the reinforcement or 50 core as rigidly as desired, so that when the lathe is turned the model or master last will be turned therewith, whereby the follower of the duplicating machine may be caused to traverse over the surface of the model 55 around and around from end to end. These last reproducing machines are too well known to require illustration herein. It is obvious that were the body 1 not provided with an adequate reinforcement, the same 60 would be liable to be broken were it attempted to use the same in such a machine. By my improved construction which includes the longitudinal reinforce, endwise pressure on the last is taken wholly by the 65 core and thus damage or breakage is completely avoided. To reinforce the external surface over which the follower of the last machine will travel, I provide an armor 5 which comprises preferably a thin fabric 70 covering which may be thoroughly impregnated with some hardening material such as glue, whereby when said glue sets, the surface of the body 1 will be made tough and 75 resistant to the action of the said follower.

The fabric may be in the form of a thin seamless sock, which so closely approximates the design of the model, that it may be caused to tightly adhere to the surface thereof so as to conform to every curve. 80

What I claim is:

1. A master-last comprising a body formed of plastic compound of a relatively fragile material, a core extending longitudinally through said last to reinforce the same 85 against endwise crushing strain.

2. A master-last comprising a body formed of a plastic compound of a relatively fragile material, a core extending longitudinally through said last to reinforce 90 the same against endwise crushing strain, with means for locking said core in said body against relative rotary movement.

MEDOREM W. GREER.
